LESTER L. WESTLING AND MILLARD R. HICKMAN, OF OAKLAND, CALIFORNIA

GAS AND LIQUID SEPARATOR

Application filed October 23, 1928. Serial No. 314,348.

This invention relates to apparatus for separating lighter particles of matter, such as gases, from liquids in which it is entrained, particularly entrained air from water, preparatory to the use of the water in boilers or for purposes generally where air mixed with the water would be objectionable.

The present application takes place of our abandoned application filed June 30, 1924, under Serial No. 723,159, and shows certain improvements in addition to the fundamentals of the device of said application.

Briefly described the apparatus comprises a vertically arranged relatively long cylinder 15 provided with means for admitting the liquid which it is desired to treat, at the bottom of the cylinder, and for taking the separated gas off at the upper end of the cylinder, while within the cylinder are arrangements to 20 cause a rapid spinning of the column of liquid so as to form a vortex along its axis along which vortex the gas or air escapes, and means for withdrawing the liquid from the upper periphery of the cylinder.

25 The objects of the present invention are to effect improvements whereby the spinning or swirling motion will be imparted to the liquid column in a manner to form a central and steady vortex, and also to provide a water 30 discharge operating in a manner to avoid objectionable influence on the vortex, or the inclusion of any of its gas in the liquid withdrawn for use.

Other objects are constructional features 35 promoting ease of assembly, cleaning and repairs.

In the drawing accompanying this application Fig. 1 is a central vertical section through our apparatus, Fig. 2 is an enlarged 40 perspective view with portion broken away showing the lower throat piece. Fig. 3 is an enlarged perspective view of the multi-vane inlet collar or device which positions at the lower end of the cylinder under the device of Fig. 2. Fig. 4 is a cross section of Fig. 1 as seen from the line 4-4 thereof.

In further detail the construction includes a main cylinder 1 flanged at opposite ends and bolted at the lower end to a circular bowl 2 50 provided with a side inlet pipe 3 adapted to

secure to a pipe 4 for supplying liquid to the separator under pressure, and under the bowl are ribs 5 forming a flat base for the cylinder to stand upon.

Within the bowl is positioned a circular 55 thimble or throat piece 6 of an internal diameter at the top to coincide with the internal diameter of the cylinder 1 and tapering smaller downwardly so as to form a thick wall at its lower end at 6'.

This device is positioned with its upper 60 rim under the inner edge of cylinder 1 and is firmly clamped down thereby against a specially vaned inlet collar 7.

Inlet collar 7 comprises a short section of 65 a metal cylinder, such as a piece of well casing, slit down its sides at a plurality of places and the metal ears thus formed bent inwardly and curved as at 7' in Figs. 2 and 3 so as to form a series of vertically disposed curved 70 vanes between which the liquid may pass from the bowl to the interior of the cylinder.

These vanes are so formed that their inlet 75 edges are parallel to the cylindrical wall of the chamber 1 and their outlet edges at an angle to the radius whereby to produce a torque upon the column of liquid in the cylinder.

Secured to the upper end of the cylinder is a bonnet 8 domed within and provided with 80 a central outlet 9, while below the dome the bonnet is enlarged into the form of an annular chamber 10 and below the chamber it is flanged and bolted to cylinder 1.

The bonnet is fitted within with a short 85 tubular section 11 of the same internal diameter of the cylinder clamped between a shoulder formed at 12 within the bonnet and the upper end of the cylinder.

Tubular section 11 is preferably made of a 90 section of well casing or the like and is perforated around its upper portion with several rows of relatively small holes, 13 leading to the upper part of chamber 10, and from one side of the lower portion of chamber 10 extends an outlet connection 15 flanged or otherwise adapted for securing to an outlet pipe 95 16 as indicated.

In use the liquid 17 with entrained gases 100 in the form of fine bubbles, is forced under

pressure through inlet pipe 4, and at the bottom of the bowl it flows through the vanes in collar 7 and is given a rapid spiral motion as it ascends upward with a result that the lighter particles form a vortex 18 at the center of cylinder to escape at the apex of its dome through outlet 9, while the liquid freed from gas or other lighter material flows outward through apertures 13 to the outlet pipe 16.

10 Owing to the arrangement of spiralling inlet ports formed by the vanes 7 around the entire circumference of the liquid column above, the force is applied evenly all around the column of liquid with a result that the vortex is centralized and is free from the objectionable tendency to "whip" encountered with prior construction and which affected the purity of the liquid withdrawn after separation.

15 20 The throat 6 positioned above the peripheral vanes 7 insures a maximum effect of the vanes upon the liquid before dissipation of the force of the liquid upwards, and has an important effect in preventing turbulence of the column and consequent disruption of the vortex.

25 30 The arrangement of small holes 13 around the entire inner circumference of sleeve 11 insures a perfectly even outward flow of separated liquid from the column without disturbing the vortex, probably due to the breaking up of the outflow into small units under precisely similar conditions entirely around the gas vortex.

35 40 It may be remarked here that this device has been found to separate gases from liquids when there is scarcely any velocity to the liquid in passing through the device, as a separation will still take place by flotation due to the design of the separating chamber.

45 50 We realize that many forms of centrifugal separators for handling all kinds of material have been made but we believe the features above described to be original with us and therefore.

We claim:

55 60 1. A separator of the character described comprising an upright cylinder provided with a plurality of spirally arranged inlets spaced around its lower end, an annular chamber connecting said spiral inlets and provided with a supply inlet, said cylinder provided with a gas discharge port at the top of the cylinder and a plurality of outlet ports formed around the inner circumference of the cylinder below said discharge port.

65 70 2. A separator of the character described comprising an upright cylinder provided with a plurality of spirally arranged inlets spaced around its lower end, an annular chamber connecting said spiral inlets and provided with a supply inlet, said cylinder provided with separate ports at the top of the cylinder arranged respectively for the discharge of

gas and liquid, and a cylindrical throat piece positioned at the lower part of the cylinder on top of said spirally arranged inlets.

75 3. In a structure as specified in claim 1, a chamber formed around the said outlet ports open thereto and extending substantially below said outlet ports.

80 4. A separator of the character described comprising a cylinder, a bonnet on one end of said cylinder, a tubular sleeve in said bonnet of a diameter to continue the bore of the cylinder, said bonnet being annularly chambered outside of said sleeve and the sleeve apertured to said chamber, a gas outlet at the end of the bonnet, an outlet from the chamber, an inlet to the opposite end of the cylinder, and means adjacent said inlet arranged and adapted for imparting a twirling motion to a liquid forced through said inlet.

85 5. A separator of the character described comprising a cylinder, a bonnet on one end of said cylinder, a tubular sleeve in said bonnet of a diameter to continue the bore of the cylinder, said bonnet being annularly chambered outside of said sleeve and the sleeve apertured to said chamber, a gas outlet at the end of the bonnet, an outlet from the chamber, an inlet to the opposite end of the cylinder, and means adjacent said inlet arranged and adapted for imparting a twirling motion to a liquid forced through said inlet comprising a plurality of spirally arranged vanes positioned within and around the end of the cylinder.

90 100 6. A separator of the character described comprising a cylinder, a bonnet on one end of said cylinder, a tubular sleeve in said bonnet of a diameter to continue the bore of the cylinder, said bonnet being annularly chambered outside of said sleeve and the sleeve apertured to said chamber, a gas outlet at the end of the bonnet, an outlet from the chamber, an inlet to the opposite end of the cylinder, and means adjacent said inlet arranged and adapted for imparting a twirling motion to a liquid forced through said inlet comprising a plurality of spirally arranged vanes positioned within and around the end of the cylinder and an internally tapered throat piece overlying said vanes.

105 110 7. A gas-liquid separator of the character described, comprising an upright cylinder provided with a supply inlet at its lower end and a gas discharge at its upper end, means within the lower end of the cylinder arranged and adapted for causing a twirling of a column of liquid forced through the cylinder, an annular chamber around the upper end of the cylinder provided with an outlet port at the lower portion of said chamber and a plurality of ports around the inner circumference of the cylinder opening to the upper portion of said chamber only.

115 120 125 8. A gas-liquid separator of the character

- described, comprising an upright cylinder provided with a supply inlet at its lower end and a gas discharge at its upper end, means within the lower end of the cylinder arranged 5 and adapted for causing a twirling of a column of liquid forced through the cylinder, an annular chamber around the upper end of the cylinder provided with an outlet port at the lower portion of said chamber and a 10 plurality of ports around the inner circumference of the cylinder opening to the upper portion of said chamber only a row of said ports being positioned to open adjacent the upper wall of said chamber.
- 15 9. In a structure as specified in claim 7, the portion of the cylinder extending through said chamber formed of a tubular section fitting within a bore in said chamber.
